UNITED STATES PATENT OFFICE.

FRANK M. STEVENS, OF DES MOINES, IOWA, ASSIGNOR TO THE ARMAND COMPANY, OF DES MOINES, IOWA.

VANITY CASE.

Application filed July 9, 1923. Serial No. 650,286.

To all whom it may concern:

Be it known that I, FRANK M. STEVENS, a citizen of the United States, and a resident of Des Moines, in the county of Polk and State of Iowa, have invented a certain new and useful Vanity Case, of which the following is a specification.

The object of my invention is to provide a vanity case, especially adapted for containing toilet articles in powder form, the parts of the case being very simple wherein it can be easily manufactured and marketed at a comparatively low cost.

More particularly, my invention relates to a vanity case formed of a pair of tubular members arranged to be fitted together for forming a complete container and arranged with openings for permitting the contents from within the container to be withdrawn, and to provide novel means for holding the pair of members against separation.

Still a further object is to provide a vanity case comprising a pair of tubular members arranged with overlapping portions and one of the members being formed with the knurled bead, and the other member being formed with a tongue arranged to extend into the groove formed by the knurled bead wherein the members may be rotated relative to each other and yet not being separated, the knurled bead forming a finger engaging part.

Still another object is to provide a pair of members fitted together and provided with overlapping portions with means formed on one of the members to frictionally engage the inner wall of the other and thus prevent undesired accidental rotation of one member relative to the other.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is a perspective view of my improved vanity case.

Figure 2 is a central, sectional view through the same.

Figure 3 is a side elevation of one of the members forming a part of the case, showing the engaging tongue thereon.

Figure 4 is a sectional view taken on line

4-4 of Figure 3 showing the tongue in section.

Figure 5 is an enlarged, detail view showing the construction of the knurled part on one of the members and coacting tongue on the other member received therein; and

Figure 6 is a horizontal sectional view taken on line 6-6 of Figure 2.

In the accompanying drawings, I have used the reference numerals 10 and 11 to indicate generally a pair of tubular members arranged to partially fit on over another, as clearly shown in Figure 2, in order to form a complete container.

The member 10 has its upper end curved, as at 12, and forms substantially a cover or cap for the member 11. The member 11 is provided with a flat bottom 13 so that the entire case may be stood on end.

The member 10 is provided with a knurled bead 14 wherein an interior groove 15 is formed on the inner side of the member 10, as clearly shown in Figure 2 of the drawings.

The knurled bead 14 forms a finger engaging part on the outside of the member 10 wherein it may be conveniently grasped by the fingers and easily rotated for the purpose hereinafter more fully set forth.

The member 11 is provided with an annular bead 16 against which the lower edge of the member 10 may rest. The bead 16 limits the movement of the member 10 upon the member 11.

In order to properly hold the member 10 upon the member 11, I form a pair of tongues 17 from the material of the walls of the member 11. The tongues are positioned above the beads 16 and on the portion of the member 11 which is overlapped by a portion of the member 10.

The tongues 17 are formed by blanking out a part of the material of the member 10 and springing the tongues 17 outwardly.

The tongues are formed with two parts A and B. The part B is inclined a considerable amount and is received in the groove 15 formed by the bead 14. The part A is substantially parallel with and projects beyond the main body portion of the member 11 and is designed to frictionally engage a portion of the inner wall of the member 10, as clearly illustrated in Figure 5 of the drawings.

The portion A of the tongue 17 engages

the member 10 to such an extent that it will prevent rotation undesired of either of the members relative to each other.

The portion B of the tongue 17, fitting 5 into the groove 15, will prevent any possible separation of the members 10 and 11 or any lateral movement of them relative to each other.

The member 11, just above the bead 16 10 is formed with an opening 18 designed to register with an opening 19 formed in the member 10 just below the bead 14.

The openings 18 and 19 are designed to be brought in to register with each other 15 for permitting the contents within the container or case to be withdrawn.

The member 11 may be filled with any suitable powder and then the member 10 slid, thereover until after the tongues 17 20 have snapped into position where the portion B thereof will be received within the groove 15, at which time the parts will become locked against separation.

The member 10 may be rotated relative 25 to the member 11 by simply engaging the knurled bead with the fingers and holding the member 11 with the other hand so that the openings 18 and 19 may be brought to registering position.

The container may be used for ordinary 30 face powder or powdered finger nail polish, or any other suitable toilet preparation in powder form.

It will be seen that I have provided a 35 very efficient and simple vanity case wherein the knurled bead on one member serves as a convenient engaging part and at the same time serves as a groove for receiving the tongue on the other member for preventing removing of one of the members relative to the other. The tongue also functions for firmly engaging the parts and thus preventing undesired rotation of the members relative to each other, but permitting 40 such rotation when desired.

Some changes may be made in the construction, and arrangement of the various parts of my invention, without departing from the real spirit and purpose of my 50 invention and it is my intention to cover by my claims, any modified forms of structure or use of mechanical equivalents, which may be reasonably included within their scope.

I claim as my invention:

1. In a vanity case comprising a top and a bottom tubular member fitted together for forming a container, said top and bottom member having one end open and one 55 end closed, the open ends being telescoped for relative rotary movement, an annular head formed on the bottom member below

its upper end, said top member being fitted on said bottom member and having its lower end abutted against said head, an annular groove 65 opening inwardly formed on said top member above its lower end and below the upper end of the bottom member when fitted together, a resilient tongue on said bottom above the bead, said tongue having a portion arranged to frictionally engage the inner surface of the top member for preventing its accidental rotation, the lower edge of said tongue being projected into the groove in said top member for preventing 70 the separation of the top member from the bottom member, each of said members having an opening therein in their overlapping portions adapted to register with each other for permitting the contents of 75 the container to be discharged.

2. In a vanity case comprising a top and a bottom tubular member fitted together for forming a container, said top and bottom member having one end open and one end 85 closed, the open ends being telescoped for relative rotary movement, an annular head formed on the bottom member below its upper end, said top member being fitted on said bottom member and having its lower 90 end abutted against said bead, an annular groove opening inwardly formed on said top member above its lower end and below the upper end of the bottom member when fitted together, a pair of resilient tongues 95 on said bottom member adapted to be covered by the portion of the top member fitting over said bottom member, said tongues having a flat portion offset from the body of said bottom member so as to 100 be spaced out beyond the surface thereof, said flat portion being in frictional engagement with the inner surface of the top member for preventing accidental rotation thereof, the lower edge of said tongues being projected into said annular groove for 105 preventing separation of the top from the bottom member.

3. A vanity case comprising a pair of tubular members fitted together for forming a container, one of said members being formed with an inwardly opening annular groove, a tongue formed on the other of said members adapted to extend into said groove for preventing the separation of said members, a flat offset outwardly extending portion on said tongue arranged to frictionally engage the inner surface of one of said members above the groove therein for holding the members against accidental rotation relative to each other.

Des Moines, Iowa, June 26, 1923.

FRANK M. STEVENS.
